UNITED STATES PATENT OFFICE.

MICHAEL LIPTAK, OF ST. PAUL, MINNESOTA, ASSIGNOR TO A. P. GREEN FIRE BRICK COMPANY, OF MEXICO, MISSOURI, A CORPORATION OF MISSOURI.

FURNACE WALL.

Application filed September 7, 1920. Serial No. 408,699.

To all whom it may concern:

Be it known that I, MICHAEL LIPTAK, a citizen of the United States, residing at St. Paul, in the county of Ramsey and State 5 of Minnesota, have invented certain new and useful Improvements in Furnace Walls; and I do hereby declare the following to be a full, clear, and exact description of the invention, such as will enable others skilled in 10 the art to which it appertains to make and use the same.

My invention has for its object to improve the construction of furnace walls, and to such ends, generally stated, the invention 15 consists of the novel construction and combination of parts hereinafter described and defined in the claims. In many respects, the present invention is in the nature of an improvement on, or modification of the furnace wall disclosed and claimed in my pending application 394,112, filed of date, July 6th, 1920, but in some respects, the present invention is independent of the said earlier 20 application, in that it involves broadly new features not therein disclosed.

Particularly, this invention relates to wall structures comprising outer or permanent walls, and inner, or replaceable walls, which latter are subjected to intense heat, so that 25 they will burn out, at least, in places, and require replacement or repair many times during the life of the outer or permanent wall. This invention makes replacement and repair of the inner wall a comparatively 30 simple and easy matter, and reduces to a minimum the cost of maintenance of furnace walls. In the accompanying drawings which illustrate the invention, like characters indicate like parts throughout the 35 several views.

Referring to the drawings:

Fig. 1 is a fragmentary perspective illustrating a furnace wall, designed in accordance with my invention.

Fig. 2 is a vertical transverse section, taken on the line 2—2 of Figure 1.

Fig. 3 is a horizontal section on the line 3—3 of Figure 1.

Fig. 2^A is a view corresponding to Figure 2, but illustrating a slightly modified construction of the wall.

Fig. 4 is a perspective showing one of the box-like metallic anchors, of the outer wall looking at the inner face thereof.

Fig. 5 is a perspective of the same ele-

ment as shown in Figure 4, looking at the outer face thereof.

Fig. 6 is a view corresponding to Figure 5, but illustrating a modified form of the box like anchor. 60

Fig. 7 is also a view corresponding to Figure 5 but illustrating a still further modified construction of the box like anchor.

Fig. 8 is a perspective illustrating a modified arrangement in which several box-like 65 anchors are put together in a way different from all the other illustrations.

Fig. 9 is a perspective showing one of the anchoring tiles of the inner wall.

Fig. 10 is a perspective showing a key 70 tile for cooperation with each anchoring tile shown in Figure 9.

The outer or permanent wall, in this preferred arrangement illustrated in the drawings, comprises horizontally extended wall 75 sections made up of commercial bricks 11, laid in a multiplicity of layers, and between the wall sections of commercial brick, interposed layers made up in whole or in part of metallic anchors. These metallic anchors 80 may take different forms but in the preferred arrangement they are box-like channels or beams, preferably cast and extended from the one buckstay to the other. In the drawings the buckstays 12, are shown as of 85 standard or well known construction, and each comprising a pair of channel beams set back to back but spaced slightly apart. In the preferred arrangement, as above indicated, the box-like metallic anchors are indicated as entireties by the numeral 13 and are long enough to extend horizontally from the one buckstay to the other. At their abutting ends the anchoring boxes 13 are preferably rigidly connected by short nut 90 95 equipped bolts 14, passed through the end walls thereof.

At their outer sides adjacent to the buckstays the anchor boxes 13 are formed with T-shaped slots 15 which extend to enlarged 100 bolt head passages 16. These anchoring boxes are laid end to end on top of and underlying brick wall section 11 and they are arranged to be securely anchored to the buckstays 12, by nut equipped bolts 17. The 105 heads of these bolts 17 may be inserted into the T-shaped slots 15 through the bolt head passages 16.

Close adjustments or accurate spacing of the buckstays are not necessary because the 110

bolts 17 can slide horizontally in the slots 15 and vertically in the spaces between the channels of the buckstays, until they are tightened when in final position.

5 When the anchoring boxes are made very long they may be reinforced at the intermediate portions by vertical webs 18. The anchoring boxes are in a direction transversely of the wall, considerably narrower 10 than the outer wall brick work or masonry sections 11, and at their inner faces they are open but are provided at the inner edge of their bottom plates with up standing lock flanges 19, for an important purpose which 15 will presently appear.

The inner wall is made up of horizontal wall section of fire brick masonry 20, laid in a multiplicity of horizontal courses, and between these fire brick wall sections, horizontal 20 layers of anchoring tiles 21 and key tiles 22. The anchoring tiles 21 are of such length that they extend entirely through the inner wall and far into the anchoring boxes 13 of the outer wall. In their bottoms the anchoring tiles 21 are provided with lock 25 notches 23, that affords shoulders that interlock with the lock flanges 19 of the lock boxes 13, see particularly Figure 2, by reference to which it will be noted that the notches 23 are located a very considerable 30 distance from extreme outer or box-engaging ends of said tiles. Also it will be noted that the key tiles 22 when inserted into the anchor box positively hold the underlying 35 anchoring tiles down and interlocked to the box flanges 19.

Preferably the tiles 21 are laid side by side, and the superimposed key tiles are laid side by side so that they together form a shelf 40 interlocked to and projecting from the anchoring boxes 13. Again by referring to Figure 2 it will be noted that considerable portions of the anchoring tiles 21 beyond the notches 23 are firmly seated on the inner 45 portion of the upper surface of the underlying outer wall section 11. This gives the shelf formed by the tiles 21 and 22 a long bearing in the outer wall supported to points inward of the notches 23, which latter of course 50 somewhat weaken the tiles 21, where they are formed. The arrangement described also incorporates the key tiles into the shelf structure in such manner that their load carrying strength is contributed to the 55 shelf structure.

The lowermost fire brick inner wall masonry section 20 is built upon the foundation, while upper masonry sections 20 are built upon shelves afforded by tiles 21 and 60 22, so that any one of the said masonry sections 20 may be removed and replaced in whole or in part without disturbing the outer or permanent wall, and when desired without disturbing the shelf structures.

65 When the tiles 21 and 22 or either thereof

require replacing, that is also an easy matter, since it is only necessary first to remove an overlying key tile, 22, and then to remove the underlying anchoring tile, by first lifting the same off from the lock flange 19, 70 then removing it endwise. It of course goes without saying that the anchoring tiles 21 are anchored to the anchor boxes after they have been properly inserted by dropping the same until their notches 23 engage the 75 lock flanges 19.

The construction concluded in Figure 2^A is like that illustrated in Figures 1 and 2, except that the tiles 21 and 22 are made a little longer so that the inner and outer walls 80 are spaced, either to afford an air space or to afford a space that is filled with insulating material 24.

The anchor box 13, shown in Figure 6, is like that shown in Figure 5, and certain 85 other views, except that the T-shaped bolt slot 15^a, extends from end to end of said box and terminates in bolt head entrance passages 16^a.

The anchor box shown in Figure 7, is like 90 that shown in Figure 6 except that the T-shaped bolt slot 15^b is short, extends only through the intermediate portions of said box and terminates in bolt head entrance 95 passages 16^b.

The anchor boxes shown in Figure 8, are like those illustrated in Figure 6, except that they are shorter, so as to leave spaces therebetween for short cast metal anchor boxes 13^a, that are like the boxes 13 of this view 100 Figure 8, except that the bolt slots and entrance passages are omitted at the back thereof.

Some furnace walls are so built that they do not require buckstays and in such walls 105 the anchor boxes would preferably be formed with plain smooth outside walls or backs. Of course from what has been said it is understood that the metallic anchors in the outer wall may take many different 110 forms and that when made of box-like formation they may be made of any desired length and applied in different ways.

What I claim is:

1. A wall structure comprising a permanent outer wall and a replaceable inner wall, 115 said outer wall having metallic anchor boxes built therein, and said inner wall having built therein anchoring tiles with ends that project into and are interlocked to said anchor boxes.

2. A wall structure comprising a permanent outer wall and a replaceable inner wall, 120 said outer wall having metallic anchor boxes built therein, said inner wall having built therein anchoring tiles with ends that project into and are interlocked to said anchor boxes, by movements transversely of their length, and key blocks inserted into 125 said boxes and against said anchor tiles, for 130

- positively holding the same interlocked to said boxes and forming elements of the inner wall. 30
3. A wall structure comprising a permanent outer wall and a replaceable inner wall, said outer wall including box like metallic anchors built therein, and said inner wall including anchoring tiles and key tiles, the former having interlocking engagement 35 with said anchor boxes, and the latter holding said anchoring tiles interlocked to said anchor boxes.
4. A wall structure comprising a permanent outer wall and a replaceable inner wall, 15 said outer wall including box like metallic anchors built therein, and said inner wall including anchoring tiles and key tiles, the former having interlocking engagement with said anchor boxes, and the latter holding 20 said anchoring tiles interlocked, to said anchor boxes, said anchoring tiles and key tiles forming a shelf that supports a masonry section of said inner wall.
5. A wall structure comprising a permanent main wall and a replaceable inner wall, 25 said main wall having pockets formed therein and said inner wall having built therein anchoring tiles with projecting ends that are detachably anchored in the pockets of
- the said main wall and afford supporting shelves for elements of said inner wall.
6. A wall structure comprising a permanent main wall and a replaceable inner wall, 30 said main wall having pockets formed therein and said inner wall having built therein anchoring tiles with projecting ends that are detachably anchored in the pockets of the said main wall and afford supporting shelves for elements of said inner wall, said inner wall further including belts of fire 35 brick built on the said shelf-forming anchoring tiles.
7. A wall structure comprising a permanent main wall and a replaceable inner wall, 40 said main wall having pockets formed therein and said inner wall having built therein anchoring tiles with projecting ends that are projected into the pockets of said main wall and have interlocking engagement therewith, key blocks also extended from 45 said replaceable wall into said pockets and holding said anchoring tiles interlocked within said pockets, said anchoring tiles affording supporting shelves for elements of 50 said inner wall.

55 In testimony whereof I affix my signature.

MICHAEL LIPTAK.
